[57] CLAIM

The ornamental design for a depth gauge, as shown and
described.

DESCRIPTION

FIG. 1 is a perspective view showing the front and
bottom of the present invention;

FIG. 2 is a front elevational view of the invention
shown in FIG. 1;

FIG. 3 is a right side elevational view of the invention
shown in FIG. 1;

FIG. 4 is a rear elevational view of the invention shown
in FIG. 1;

FIG. 5 is a left side elevational view of the invention
shown in FIG. 1;

FIG. 6 is a top plan view of the invention shown in
FIG. 1; and,

FIG. 7 is a bottom plan view of the invention shown in
FIG. 1.
